BY *Victor J. Evans*
ATTORNEY

UNITED STATES PATENT OFFICE.

EDWIN C. J. LLOYD, OF JEANNETTE, PENNSYLVANIA.

BOX AND ATTACHMENT THEREFOR.

1,423,442.

Specification of Letters Patent. Patented July 18, 1922.

Application filed August 31, 1920. Serial No. 407,120.

To all whom it may concern:

Be it known that I, EDWIN C. J. LLOYD, a citizen of the United States, residing at Jeannette, in the county of Westmoreland 5 and State of Pennsylvania, have invented new and useful Improvements in Boxes and Attachments Therefor, of which the following is a specification.

This invention relates to a box and an 10 attachment, and more particularly to a box adapted to contain shoe polish and similar materials.

This invention is intended more particularly as an improvement over the device dis- 15 closed in my co-pending application for box and attachment therefor, filed June 4th, 1920, Serial Number 386,624.

One of the main objects of the invention 20 is to provide a box having simple and ef- ficient means for detachably securing a brush or dauber to the box, this means serv- ing to protect the head of the brush. A further object is to provide simple and ef- ficient means whereby a brush having bris- 25 tles disposed at right angles to the brush handle may be readily accommodated and protected. Another object is to provide a brush and a box top or cover so related that the brush may be used in opening the box.

30 Further objects will appear from the detailed description.

In the drawings:

Figure 1 is a top plan view of a box and a brush attached thereto constructed in ac- 35 cordanee with my invention.

Figure 2 is a section taken substantially on line 2--2 of Figure 1.

Figure 3 is an edge view of the box looking at the head of the brush.

40 The box is of known type consisting of an upper or top section 1 and a lower section 2. Upper section 1 is provided in its top wall with a groove 3 extending diametrically of the same, this groove being of dovetail cross section. The groove communicates at its 45 inner end with a relatively deep recess 4 which is adapted to receive a head 5 of a brush 6 the handle 7 of which is of dovetail cross section and fits snugly in groove 3, the 50 combined length of head 5 and handle 7 corresponding to the combined lengths of re-

cess 4 and groove 3. By inserting handle 7 into groove 3, the brush may be readily at- tached to upper section 1 of the box in such manner that bristles 8 of the brush are posi- 55 tioned within and protected by recess 4.

By withdrawing the brush from groove 3 and recess 4, and inserting handle 7 into the groove from the outer end thereof with the head of the brush projecting beyond upper 60 section 1, the brush may be gripped so as to facilitate removal of upper section 1 for opening the box. By having bristles 8 dis- posed at right angles to handle 7, the use of the dauber for applying polish is greatly fa- 65 cilitated, and soiling of the hands when using the device in opening the box is pre- vented; while the bristles are protected and enclosed by the walls of recess 4 when the dauber is in its normal position in upper 70 section 1 of the box. As will be understood, if desired upper section 1 of the box may be used to contain the polish or other material, the lower section being made relatively shal- 75 low and forming a closure member. Also, groove 3 instead of being of dovetail cross section may be of any other cross section suitable for the purpose intended, the handle 7 of the dauber being of corresponding cross section. 80

What I claim is:—

1. In combination with a box including a cover provided with a dovetail groove and a relatively deep recess communicating therewith and open at its outer end, a brush 85 including a handle fitting snugly within the groove and a head positioned within said recess and including bristles disposed at right angles to said handle.

2. In combination with a box including a 90 cover provided with a diametrically extend- ing dovetail groove and a recess communica- 95 ting with the groove at one end thereof and open at its outer end, said recess being of greater depth than said groove, a brush including a handle fitting snugly within the groove and a head positioned within said recess and including bristles disposed at right angles to the handle.

In testimony wherof I affix my signature. 100

EDWIN C. J. LLOYD.
